UNITED STATES PATENT OFFICE.

SAMUEL G. MARGLES, OF BROOKLYN, NEW YORK, AND CHARLES W. E. NIENDORFF, OF JERSEY CITY, NEW JERSEY, ASSIGNORS TO OTIS ELEVATOR COMPANY, OF JERSEY CITY, NEW JERSEY, A CORPORATION OF NEW JERSEY.

ENDLESS CONVEYER.

Application filed September 23, 1921. Serial No. 502,825.

To all whom it may concern:

Be it known that we, SAMUEL G. MARGLES and CHARLES W. E. NIENDORFF, citizens of the United States of America, residing, respectively, in Brooklyn, county of Kings, State of New York, and Jersey City, in the county of Hudson and State of New Jersey, have invented a new and useful Improvement in Endless Conveyers, of which the following is a specification.

Our invention relates to incline endless conveyers, and has to do with certain improvements in conveyers more particularly of the step type commonly known as escalators, having a double chain drive. Essentially the invention consists in certain modifications in construction and arrangement of parts, such changes in effect tending toward simplicity and cheapness, and the overcoming of certain objectionable features, which objectionable features will be pointed out fully hereinafter.

One of the objects of the invention is the insertion of the outer, or what is known as the front step wheels within the chain links of the drive chains forming a part thereof.

Another object of the invention is, using a three point suspension, which requires comparatively little accuracy in carriage alignment, and permits the use of one single tracked carriage of circular curvature at the upper landing and one at the lower landing, instead of two double tracked carriages of "constant speed" curvature at each landing.

A further object of the invention is in the construction of the steps, the effect tending toward simplicity, the steps accommodating either flat treads or cleat treads.

A still further object is the elimination of the see-saw movement in the present invention of an escalator, and that no additional devices or parts are used to overcome this undesirable feature, inherent in most step type conveyers, especially in the single chain drive type.

With the above objects in view, the invention consists in the apparatus hereinafter described and illustrated in the accompanying drawings, in which:

Figure 1 illustrates in longitudinal section a side view of the upper landing, and a portion of an escalator constructed in accordance with the present invention.

Figure 2 illustrates a similar view of the lower landing and of the escalator.

Figure 3 illustrates a partial section on line *a-a* of Figure 1, looking in the direction of the arrows.

Figure 4 illustrates a partial section on line *b-b* of Figure 2, looking in the direction of the arrows.

Figures 5 and 6 illustrate respectively, side views of the upper and lower carriages, the views embodying a section of a track, together with its extension, the track and extension being located on the side opposite to the carriage.

Figures 7 and 8 are respective plan views of Figures 5 and 6 the steps in either case not being shown.

Figures 9 and 10 illustrate enlarged longitudinal views of a step with chain attached, both being partly in section, the step in one instance accommodating a flat tread, the other a cleat tread respectively.

Figure 11 illustrates a plan view of Figures 9 and 10 together, with chain attached, the position of the steps in this instance being somewhere on the incline of the escalator.

Figure 12 is a front end elevation of the cleat tread type of step in Figure 11.

Like reference characters denote similar parts in all of the figures.

The conveyer comprises a series of steps *A*, which form an endless movable tread platform or surface connecting different floor levels *B* and *C*. The tread surface proper of each step may be either the rib or plain type. The former type of tread is used with the steps in Figure 1, and referring to Figures 10, 11 and 12, comprises longitudinal ribs, *1*, producing the relatively shallow grooves, *2*, between the said ribs, the ribs being suitably secured, which securing points are not shown, to a horizontal recessed web, *3*, forming an integral part of a one piece step frame, *4*. A usual form of comb landing, *D*, Figure 1, is provided at the floor level, the comb having teeth or prongs adapted to register with the grooves, *2*, of the steps. The latter type of tread, so-called the plain or flat tread, *5*, is used with the steps in Figure 2, and referring to Figures 9 and 11, is shown placed within the recessed web, *3*, and suitably secured thereto, the securing

- points, as in the previous types of step, not being shown. The escalator in this instance is commonly called the shunt type, the load carried being directed to one side or shunted 5 from the escalator, when the floor level is reached by means of balustrading, E, the floor landing, which is the floor level, B, in this instance, being level with the horizontal run of the escalator.
- 10 The above description tends to effect attention to the fact that the step used with the present invention of an escalator will accommodate either the rib or flat tread, without any additional parts to the steps or escalator proper.
- 15 Each step proper, as hereinbefore pointed out, is made up of one piece, comprising more essentially the horizontal web, 3, and a plain curved riser, 6. Referring to Figures 9 to 12 inclusive, to the riser, 6, at its lower end, is welded an axle, 7, which carries, at its outer ends, rear inner step wheels, 8, and axle collars, 9, which are secured to the axle by pins, 10. A pair of outer, or 20 what may be termed the front step wheels, 11, are carried at the outer ends of separate axles, 12, supported by a pair of separated bearings, 13, which are welded to the step frame. To the riser, 6, of each step and 25 each finger, 14, of bearings, 13, there is welded respectively the ends of two angle braces, 15. The rear and front step wheels are adapted to travel respectively on suitable track rails such as 16 and 17. The 30 track rails are arranged in a well known manner to form a horizontal run at the landings and an incline run between the landings, these rails forming an upper and lower run for the steps, and being united on one 35 side at the upper level by a suitable carriage, 18, the rails on the other side being united by a suitable track extension, 19, see Figures 5 and 7. In a similar manner the 40 rails are united at the lower level to another carriage, 20, on the side opposite to that of the carriage, 18, at the upper level, the rails on the other side at the lower landing are united to another suitable track extension, 21, see Figures 6 and 8.
- 45 There is provided for the purpose of driving the steps, two endless chains, 22, arranged on a center line coinciding with the center line of sprockets, 23 and 24, of which there are four in number, two at each floor 50 level, only one of each sprockets, 23 and 24, being shown, as seen in Figures 1 and 2.
- 55 The driving chains in the present instance comprise a series of links, pivotally connected with the front wheel axles, 11, to form 55 the endless chain, 22. The driving chains pass around sprocket wheels, 23 and 24, at the lower and upper landings, respectively. Either one or both of these sprocket wheels 60 may be driven from any suitable source of power. The sprocket wheels are construct-

ed with cut-out portions such as, 25, to accommodate the front step wheels, 11, and cutout portion such as, 26, to accommodate the spacers or bushings, 27, of the chains. The chains are so constructed that the links 70 between the step axles, 12, will form a rigid or straight line connection between the axles while the chains are in commission on the upper run of the escalator, while at the same time it will accommodate, or in other words, 75 flex or bend around the sprocket wheels, 23 and 24, in the same manner as an ordinary chain, and pass through the various curved tracks forming the lower run, with perfect freedom.

80 The construction of the driving chains to admit of the above noted characteristics is shown in Figures 9, 10 and 11. Referring more particularly to Figure 11, therein is illustrated only a portion of each endless 85 chain such as connects adjacent front step axles. The front step axles are connected by a number of links of each chain, the links in the present instance being six in number, taking them collectively, that is links opposite each other, so as to describe them more clearly, which I will designate, 28, 28' and 28'', referring to one of the chains only, as the other is identical. One end of each of the links, 28 and 28'', is pivotally connected 90 with the step axles, 12, their other ends are pinned to opposite ends of the links, 28', between which are spacers or bushings, 27, this construction of the links of the chain is only 95 between adjacent front step axles, the other 100 links of the chain are plain so to speak, for an illustration, the links which I will designate, 29, may be thought as being a continuation of links, 29'. To cause the chain to form a rigid or straight line connection, 105 and also to accommodate itself to flex or bend as pointed out heretofore, there is formed integral with one end of each of the links 28 and 28'' and both ends of the links, 28', projections 30 and 30', respectively, 110 which co-act with each other, resulting in the heretofore statement.

An important feature not spoken of heretofore in the construction of this class of apparatus, is the placing of each of the front 115 step wheels of each step within each of the chains; as a result of this combination, each of the said wheels become a part of, or as a result, practically constitutes a part of each chain. With the above construction the 120 downward thrust encountered taking place at the curved track portion of the escalator which connects the incline working run with the upper horizontal run is taken up at the point indicated by the front step wheels 125 within the chain and their co-acting tracks, the action in the present case resulting in a shear, the parts, namely the step and chains traveling relatively to each other in a direction parallel in their plane of contact. Ac- 130

cording to this feature in the present invention we eliminate the use of weighty parts of large dimensions such as the step axles, as they are eliminated from strain, this item 5 being of considerable importance since it tends materially to reduce the cost of the apparatus. The steps in the present case are not limited as to their width as the downward pull of the chain is at the outside of 10 the steps proper, and not on a line central with the center line of the steps, as in the single chain drive type of escalator in which case the steps are limited as to their width. It was stated heretofore that only one carriage 15 18 and 20 is used at each landing B and C respectively, to help, together with each of the two sprockets 23 and 24 respectively, to guide the steps from their righted to inverted position and vice versa in the 20 operation of the escalator and that they were at opposite sides to each other. For the latter reason, that of being opposite to each other, is to cause the rear step wheels, they being the ones that engage the carriage, to 25 wear equally, which they would not if both carriages were on the same side of the escalator. The former reason, that of using only the one carriage at each landing eliminates the using of two carriages, they having to 30 be of such a design to prevent wrenching the steps at this point. In the present case only one carriage is used as a guide; we thus have a three point suspension as shown in Figures 3 and 4, which requires comparatively 35 little accuracy in carriage alignment.

Having thus described our invention, what we claim and desire to secure by Letters Patent of the United States is:

1. In an endless conveyer, comprised of 40 transporting sections, having carrying wheels at the front and rear of the sections on either side thereof, driving chains and sprocket wheels for the sections at the end of the way, one track in alignment with and

ending at the sprocket wheels, and the other track extended along the sprocket wheels and beyond the first mentioned track.

2. In an escalator, comprised of steps, front wheels for the steps, and a driving chain comprising links, the wheels journaled between the links of the chain, and a way for the wheels.

3. In an escalator, comprised of steps, driving chains of double links for the steps outside of the ends of the steps, wheels for 55 the front of the steps journaled between the double links, and ways for the wheels.

4. In an escalator, having a step, pairs of front and rear wheels for the step, one pair being outside of the other pair, ways on the 60 sides of the escalator for the wheels, the ways comprised of rails or tracks, track extensions and curved carriages, the extensions being at one end of the rails and the carriages at the other end, at alternate ends of 65 the ways, one of the tracks of each way being shorter than the other track of that way, sprocket wheels, at the ends of the shorter tracks, adapted to receive the outside wheels.

5. In an escalator, having a step, two pairs 70 of front and rear wheels for the step, one pair being outside of the other pair, ways on the sides of the escalator for the wheels, the ways comprised of tracks, track extensions and curved carriages, the extensions and 75 carriages being at alternate ends of the ways, the extensions and carriages of one of the tracks of each way being projected beyond the extensions and carriages of the other track of that way, sprocket wheels at 80 the ends of the shorter tracks, and extending along the side of the ends of the longer tracks, adapted to receive, at the ends of the ways, the outside wheels.

In testimony whereof we have signed our names to this specification.

SAMUEL G. MARGLES.

CHARLES W. E. NIENDORFF.
